(57) **CLAIM**

The ornamental design for a post top mount for a floodlight fixture, as shown and described.

DESCRIPTION

FIG. 1 is a front top perspective view of a post top mount for a floodlight fixture.

FIG. 2 is a front bottom perspective view of the post top mount of FIG. 1.

FIG. 3 is a front elevation view of the post top mount of FIG. 1, a rear elevation view being a mirror image.

FIG. 4 is a right-side elevation view of the post top mount of FIG. 1, a left-side elevation view being a mirror image; and, FIG. 5 is a bottom plan view of the post top mount of FIG. 1. The broken lines are provided for illustrative purposes only and form no part of the claimed design.
